UNITED STATES PATENT OFFICE.

FRANK K. BERRY, OF BATTLE CREEK, MICHIGAN, ASSIGNOR TO A-B STOVE COMPANY,
OF BATTLE CREEK, MICHIGAN, A CORPORATION OF MICHIGAN.

OVEN-DOOR.

1,111,352.

Specification of Letters Patent. Patented Sept. 22, 1914.

Application filed June 16, 1913. Serial No. 773,995.

To all whom it may concern:

Be it known that I, FRANK K. BERRY, a citizen of the United States of America, residing at Battle Creek, in the county of Calhoun and State of Michigan, have invented certain new and useful Improvements in Oven-Doors, of which the following is a specification, reference being had therein to the accompanying drawings.

The invention relates to oven doors having transparent panels for inspection within the oven, and consists in the means employed for positioning and securing the glass panel as hereinafter set forth.

In the drawings: Figure 1 is a sectional perspective view of the door; and Fig. 2 is a cross section on the line $\alpha-\alpha$ of Fig. 1.

A is a door frame, preferably formed of cast metal and provided with an open center.

B is a transparent panel for the open center of the frame, which rests upon a suitable yielding bearing, such as a sheet of asbestos C adjacent to the frame.

For centering the panel within the frame and securing the same, spacer strips D are formed of sheet metal bent into a channel section, the outer flange E bearing against the concave inner face of the frame A, and the flange F forming a shoulder adjacent to the edge of the glass. The flange F will thus center the glass, and to hold it from disengagement from said flange, portions thereof are struck outward to form glass-retaining fingers G. The spacers D are secured at the corners of the frame, preferably by being provided with overlapping portions H and I which are secured by a bolt or rivet J to the frame A.

With the construction as described, the

glass is securely held from displacement by its seat upon the asbestos bearing C, together with the retaining fingers G. The pressure of these fingers upon the glass is very light and sufficient clearance is provided between the edges of the spacers and the edges of the glass to permit of expansion and contraction without unduly stressing the glass.

What I claim as my invention is:

1. An oven door, comprising a frame, a glass panel seated therein, spacers between the edge of said glass panel and the edge of the frame formed of channel bars, and securing means for said spacers, one of said spacers having a portion of its edge adjacent the edge of the frame bent to extend in substantially the plane of the web portion of the spacer and beyond the edge of the panel to hold the same from disengagement.

2. An oven door, comprising an annular frame having a concavo-convex cross-section, a glass panel seated within said frame, a spacer in the concave portion of said frame interposed between the outer edge thereof and the edge of the panel, and means for securing said spacer to said frame, said spacer being of channel cross-section and having one of its flanges forming an abutment for said panel, a portion of said flange extending substantially in the plane of the web portion of the spacer and beyond the edge of the panel.

In testimony whereof I affix my signature in presence of two witnesses.

FRANK K. BERRY.
